UNITED STATES PATENT OFFICE

EDWARD GRIMM, OF CLEVELAND, OHIO, ASSIGNOR TO JAMES O. EVANS, OF CLEVELAND, OHIO

TOY PARACHUTE

Application filed November 15, 1928. Serial No. 319,519.

The invention relates to toy parachutes, and the objects of the invention are to provide a parachute having a thin floating body of soft fabric such as silk and semi-rigid connecting rods between the fabric body and the base which may represent a weight of any kind, thus making it possible for the fabric body to be propelled or pushed from an air tube or gun and remain at all times in condition for proper expansion in the air which could not be accomplished practically, if the connecting members, were cords or flexible, since, when blown from a tube the parachute body would become wrapped in the cords and would not open as it descends. Also in the present device every alternate rod is made shorter than the adjacent rod thus holding the edges of the fabric body open so as to quickly admit the air thereto. The semi-rigid rods are flexibly connected with the weight, and fabric body. To obtain these and other objects the device comprises the combination and arrangement of parts and construction of the various details, hereinafter described, illustrated in the accompanying drawings and specifically pointed out in the claims.

In these drawings; Fig. 1 is a side elevation of the parachute expanded; Fig. 2 is an enlarged vertical section of the base; Fig. 3 is a longitudinal section of the air tube or gun from which the parachute is propelled; Fig. 4 is a perspective illustrating the action of the long and short connecting rods to partially open the fabric body of the parachute when it has been discharged from the gun; Fig. 5 illustrates a cross-stitch binding for the fabric body to prevent the edge from raveling; Fig. 6 illustrates a crimped finish for the edge for the same purpose; Fig. 7 is an elevation showing a different method of connecting the rods with the weight.

In these views A represents a tube from which the parachute is blown after folding for insertion therein; B represents the depending base or weight which maintains the parachute in a vertical position when in the air. Since the parachute is small, the weight is made of wood or other light material and

preferably hollow on the underside thus presenting a cavity in which the pressure of the breath accumulates before the weight is expelled, thus causing it to rise quickly to considerable height and is cylindrical in shape to serve as a piston for propelling the parachute out of the tube; C is the flotation body of the parachute and it is composed of light silk or other light and closely woven fabric, and the edges may be cross stitched at D as shown in Fig. 5, or crimped as shown at F, in Fig. 6, or may be protected in any desired manner from raveling.

Semi-rigid rods E, E, connect the weight or base B with the body C. These rods may be made of any suitable light fibrous substances, and serve the double purpose of push rods to thrust the fabric from the tube when the base is blown upon and also serve to suspend the weight therefrom when the parachute is in the air and also serve to introduce the fabric body into the tube. These rods are made alternately short and long which has the effect of holding some of the edges of the flotation body open when the parachute begins to fall, thus more quickly admitting air to open and sustain the body.

Flexible members are employed to secure the extremities of the rods to the adjacent parts of the fabric body and base. The flexible attaching means permit folding the parts in the tube. These members may comprise cords, G attached by means of adhesive tape I as shown in Fig. 2 or may be wholly composed of bits of adhesive tape H as shown in Fig. 7.

In this manner a practical and economical method of construction for a toy parachute is provided.

Having described the invention what I claim as new and desire to secure by Letters Patent is:

1. In an aerial toy, the combination of a blow tube and a parachute to be projected therefrom, said parachute comprising a flotation body and a weight connected by shrouds, the diameter of said weight being approximately the same as the internal diameter of said blow tube, and said shrouds being composed of semi-rigid material.

2. In an aerial toy, the combination of a blow tube and a parachute to be projected therefrom, said parachute comprising a flotation body and a weight connected by shrouds, the diameter of said weight being approximately the same as the internal diameter of said blow tube, and said shrouds being composed of semi-rigid material and flexible means connecting said shrouds to said flotation body and to said weight.

10. In testimony whereof I affix my signature.
EDWARD GRIMM.
